BOOT BAG

Floyd W. Craig, 120 N. Church St., Cordell, Okla.

Filed Aug. 17, 1964, Ser. No. 81,323

Term of patent 14 years

(Cl. D87—5)

FIG. 1

FIG. 2

FIG. 1 is a front perspective view of a boot bag embodying my new design; and,

FIG. 2 is a rear perspective view thereof.

The characteristic feature of my design resides in the combination, on the boot bag disclosed, of substantially flat side, bottom, and rear surfaces in conjunction with a scalloped toe patch of a contrasting material together with a single handle strap, all as shown.

I claim:

The ornamental design for a boot bag, as shown and described.
